HAIR STYLIST'S HAIRCUTTING HELMET

Constantino J. Alevras, 542 Gruman Court,
Rivervale, N.J. 07675

Filed Apr. 3, 1975, Ser. No. 564,915

Term of patent 14 years

Int. Cl. D28—03

U.S. CL. D86—10 A

FIG. 1

FIG. 3

FIG. 2

FIG. 4

FIG. 5

FIG. 1 is a side view of a hair stylist's haircutting helmet showing my new design;

FIG. 2 is a front elevational view thereof;

FIG. 3 is a rear elevational view thereof;

FIG. 4 is a top plan view thereof; and

FIG. 5 is a bottom plan view thereof.

I claim:

The ornamental design for a hair stylist's haircutting helmet, as shown.
